CLAIM

The ornamental design for a dispenser for plate gums, as shown and described.

DESCRIPTION

FIG. 1 is a front perspective view of a dispenser for plate gums showing our new design;

FIG. 2 is a left-side elevational view thereof;

FIG. 3 is a right-side elevational view thereof;

FIG. 4 is a front-end elevational view thereof;

FIG. 5 is a rear-end elevational view thereof;

FIG. 6 is a top plan view thereof;

FIG. 7 is a bottom view thereof; and,

FIG. 8 is a reference view showing the state wherein a sheet of paper board is drawn in the same dimensions as a real dispenser commercially available with lines for folding the sheet.
